UNITED STATES PATENT OFFICE.

GEORGE T. VERREAULT, OF BUFFALO, NEW YORK, ASSIGNOR TO E. R. THOMAS MOTOR COMPANY, OF BUFFALO, NEW YORK, A CORPORATION OF NEW YORK.

DESIGN FOR A CAP FOR AUTOMOBILE RADIATOR-FILLERS.

41,596.

Specification for Design.

Patented July 18, 1911.

Application filed May 12, 1910. Serial No. 561,021. Term of patent 14 years.

To all whom it may concern:

Be it known that I, GEORGE T. VERREAULT, a citizen of the United States, residing at Buffalo, in the county of Erie and State of New York, have invented a new, original, and ornamental Design for a Cap for Automobile Radiator-Fillers, of which the following is a specification, reference being had to the accompanying drawing, forming part thereof.

The figure is a perspective view of a cap for automobile radiator fillers, showing my new design.

I claim:

The ornamental design for a cap for an automobile radiator filler, as shown.

GEORGE T. VERREAULT.
